UNITED STATES PATENT OFFICE.

FRANK G. SNYDER AND CHARLES P. MULLEN, OF PHILADELPHIA, PENNSYLVANIA.

BOBBIN OR SPOOL.

968,276.

Specification of Letters Patent. Patented Aug. 23, 1910.

Application filed August 30, 1909. Serial No. 515,302.

To all whom it may concern:

Be it known that we, FRANK G. SNYDER and CHARLES P. MULLEN, citizens of the United States, residing at Philadelphia, in 5 the county of Philadelphia and State of Pennsylvania, have invented a new and useful Improvement in Bobbins or Spools, of which the following is a specification.

This invention relates to a bobbin or spool, 10 the object being to provide a bobbin or spool out of metal whereby the life of the same will be greatly increased and at the same time the strength will be increased to such an extent that all danger of the bobbin becoming broken is prevented.

Another object of the invention is to provide a spool or bobbin which is so constructed that the same can be manufactured very cheaply.

20 Another object of the invention is to provide a spool or bobbin in which the parts are so connected that they will be firmly held together so that all danger of the parts becoming accidentally detached is prevented.

25 With these objects in view, the invention consists in the novel features of construction, combination and arrangement of parts hereinafter fully described, pointed out in the claims and shown in the accompanying drawings, in which,

Figure 1 is a perspective view of our improved bobbin or spool. Fig. 2 is a longitudinal section through the same.

In carrying out our improved invention 35 we employ a body A which is preferably formed of a tube having contracted portions A' which terminate in outwardly projecting tubular portions A² forming bearings for the spindle upon which the bobbin or spool 40 is adapted to be placed. Arranged over the tubular portions A² of the body A are wooden plugs B which are provided with square ends and concavo-convex inner ends adapted to fit snugly over the contracted 45 portions A' so that the bearing portions will be reinforced in such a manner that all danger of the same moving or yielding in any way is prevented.

Arranged over the plugs and body A is a 50 metal tube C which is provided with flanged ends C' and annular crimped portions C²

forming flanges between which the edges of disks D', D² are adapted to fit, said disks forming end members D for the spool and are connected together at their edges by 55 bending the periphery edges annularly and crimping the same together as shown at D³. The space between the disks D', D² is filled with a suitable composition E for strengthening the same and it will be seen that by 60 this arrangement the end members are securely held in position on the tube C so that all danger of the same becoming detached is prevented.

For securing the wooden plugs in the respective ends of the tube we indent the tubes annularly as shown at C⁴ so that the indentations will be embedded in the plugs which will securely hold the same therein and said plugs will prevent the body A from moving 70 longitudinally within the tube C.

From the foregoing description it will be seen that we have provided a spool or bobbin which is formed of metal with the exception of the wooden plugs and said plugs 75 are so covered by the parts of the spool that they are not subject to any wear.

What we claim is:

1. A spool or bobbin comprising a body provided with contracted portions terminating in tubular bearing portions, plugs arranged over said tubular bearing portions, a tube arranged over said body provided with spaced flanges adjacent its ends and sectional end members arranged between 80 said flanges.

2. A bobbin or spool comprising a body having contracted portions terminating in tubular bearing portions, wooden plugs arranged over said tubular bearing portions, a tube arranged over said body having indentations embedded in said plugs adjacent its ends and provided with spaced flanges and end members formed of spaced disks secured together having the space between 95 said disks filled with composition for reinforcing the same.

3. A metal spool or bobbin comprising a tubular body portion, having contracted end portions terminating in metal bearings, 100 wooden plugs arranged over said bearings provided with concavo-convex ends fitting

snugly against the contracted portions of the body, a tube arranged over said body and plugs having annular indentations formed adjacent its ends for securing the 5 plugs in position therein, said tube being provided with spaced flanges adjacent its ends and disks surrounding said tubes between said flanges having their outer ends

crimped together and the space between said disks being filled with a composition.

FRANK G. SNYDER.
CHARLES P. MULLEN.
